UNITED STATES PATENT OFFICE.

PETER P. HORVÁTH, OF RACINE, WISCONSIN.

LIFE-BOAT.

1,104,992.

Specification of Letters Patent. Patented July 28, 1914.

Application filed January 23, 1914. Serial No. 813,929.

To all whom it may concern:

Be it known that I, PETER P. HORVÁTH, a subject of the King of Hungary, residing at Racine, in the county of Racine and State 5 of Wisconsin, have invented certain new and useful Improvements in Life-Boats, of which the following is a specification.

This invention relates to certain new and useful improvements in life boats, and has 10 for its principal object the provision of means for maintaining the equilibrium of a boat so as to practically eliminate danger of the same capsizing due to rocking thereof.

Briefly described, the invention resides in 15 providing in a life boat, an equilibrator adjustable from the interior of the boat so that during the floating of the boat in extremely rough water, the equilibrator may be lowered, and when the boat is in comparatively 20 smooth water, the equilibrator may be raised so as to offer less resistance to the rowing of the boat.

The invention also involves the provision 25 of means for shielding the rowers or other occupants of the boat from the force of the waves breaking against the sides of the boat.

An embodiment of my invention is illustrated in the accompanying drawing forming a part of this specification, and of which 30 a specific description will hereinafter follow, like numerals of reference being employed to designate like parts throughout the different views of the drawing in which:—

Figure 1 is a side elevation of a life boat 35 constructed in accordance with my invention: Fig. 2 is a top plan view of the same, and, Fig. 3 is a central vertical transverse sectional view thereof.

The boat is designated by the numeral 5, 40 and may be of any suitable outline or design. Centrally of the length of the boat, I provide a cross bar 6, suitably secured to the boat, preferably to the gunwales thereof, through which extends a screw 7, which also 45 extends through a cup-shaped stand 8 located on the bottom of the boat over a recess 9 in the boat keel, and provided with an internally-threaded collar 8^a to receive an externally-threaded stuffing box 10 provided 50 to prevent leakage of water from the recess 9 along the screw 7. The stand 8 is provided

with a base flange 8^b upwardly inclined to closely fit around the recess 9 and conform to the curved inner sides of the boat to which it is adapted to be directly secured. 55 The lower end of this screw carries a weight 11 constituting an equilibrator. The cup-shaped stand 8 being located over the recess 9 constitutes a housing within which the equilibrator 11 may be practically housed 60 when it is not desired to have the same extended down to a depth beneath the boat. The construction is distinguished from the prior art by providing a water-tight support for the adjusting screw of the weight, 65 this being effected by the internally-threaded collar extension 8^a of the housing stand 8, combined with the stuffing box 10.

In addition to the equilibrator above described, I preferably provide shields 12 70 mounted on the gunwales of the boat and having flexible sides 14 made of canvas, leather or like material, the free edges of which are suitably fastened, as by buttons or hooks, to the frames so that they may be 75 let down when desired, and thus not offer so great a surface to any wind which may be blowing. These shields are spaced so as not to interfere with the operation of the oars used in propelling the boat. 80

What I claim as new is:—

A boat provided centrally of its bottom with a recess, a cup-shaped housing formed with an upwardly-extending inclined flange mounted on the boat bottom to cover said 85 recess and provided with an upwardly-extending internally-threaded collar extension, a cross-bar secured to the gunwales of the boat and formed with a central opening, a stuffing-box within said collar, a screw extending through said opening and said stuffing-box and a weight on the lower end of said screw adapted to be adjusted by the screw and to be housed within said cup-shaped stand. 90

In testimony whereof I affix my signature in presence of two witnesses.

PETER P. HORVÁTH.
